FIG. 1 is a front elevational view of a bottle with cap, showing my new design, the rear elevational view being the same;

FIG. 2 is a side elevational view thereof, the opposite side being the same;

FIG. 3 is a top plan view thereof;

FIG. 4 is a bottom plan view thereof;

FIG. 5 is a view similar to FIG. 1 showing a second embodiment of my design, the rear elevational view being the same;

FIG. 6 is a side elevational view of the second embodiment, the opposite side being the same;

FIG. 7 is a top plan view of the second embodiment; and,

FIG. 8 is a bottom plan view of the second embodiment. The broken lines showing the dispensing nozzle in FIGS. 1 and 2 are for illustrative purposes only and do not form part of the claimed design.

*FIG. 5**FIG. 6**FIG. 7**FIG. 8*
